TOY SPARKING PISTOL

Samuel Hoffman, Newark, N. J.

Application December 16, 1952, Serial No. 22,729

Term of patent 7 years

(Cl. D34—15)

To all whom it may concern:

Be it known that I, Samuel Hoffman, a citizen of the United States, residing in the city of Newark, county of Essex, and State of New Jersey, have invented a new, original, and ornamental Design for a Toy Sparking Pistol, of which the following is a specification, reference being had to the accompanying drawing, forming a part hereof, in which:

Fig. 1 is a top plan view of a toy sparking pistol, embodying my new design;

Fig. 2 is a side elevation thereof;

Fig. 3 is a bottom plan view thereof;

Fig. 4 is a front elevation thereof; and

Fig. 5 is a rear elevation thereof.

I claim:

The ornamental design for a toy sparking pistol, as shown.

SAMUEL HOFFMAN.
